DESIGN FOR A DRINKING VESSEL OR THE LIKE

Isabella F. Scott, Atlantic City, N. J.

Application July 27, 1933, Serial No. 48,850

Term of patent 7 years

To all whom it may concern:

Be it known that I, ISABELLA F. SCOTT, a citizen of the United States, residing at Atlantic City, in the county of Atlantic and State of New Jersey, have invented a new, original, and ornamental Design for a Drinking Vessel or the like, of which the following is a specification, reference being had to the accompany drawing, forming part thereof.

Figure 1 is a view in elevation of the handle side of the drinking vessel or the like embodying my design;

I claim:—

The ornamental design for a drinking vessel or the like, as shown.

ISABELLA F. SCOTT.
